Assistant Examiner — Katherine E Morris

(57) **CLAIM**

The ornamental design for a container assembly, as shown and described.

DESCRIPTION

FIG. 1 is a first perspective view of a container assembly showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is the opening state of the box thereof; and,

FIG. 10 is an exploded view of the box thereof.

The broken lines shown in the drawings depict portions of the container assembly that form no part of the claimed design.

1 Claim, 10 Drawing Sheets
